Harvey J. Wier, Sr., Opelousas, La.

Application March 6, 1953, Serial No. 23,923

Term of patent 14 years

(Cl. D44—10)

To all whom it may concern:

Be it known that I, Harvey J. Wier, Sr., a citizen of the United States of America, residing at Opelousas, in the parish of St. Landry and State of Louisiana, have invented a new, original, and ornamental Design for Lazy Susan Chafing Dish Vehicle, of which the following is a specification, reference being had to the accompanying drawing, forming part thereof.

In the drawing

Fig. I is a perspective view of a lazy susan chafing dish vehicle showing my new design;

Fig. II is a front elevational view of the device shown in Fig. I;

Fig. III is a plan view of the device shown in Fig. I, as seen from above.

I claim:

The ornamental design for a lazy susan chafing dish vehicle, as shown.

HARVEY J. WIER, SR.
